REMOVAL OF VANADIUM AND/OR SODIUM FROM PETROLEUM AND PETROLEUM PRODUCTS WITH FULLER'S EARTH

Frederick William Bertram Porter and Roy Purdy Northcott, Sunbury-on-Thames, Middlesex, England, assignors to The British Petroleum Company Limited, a British joint-stock corporation

No Drawing. Application June 16, 1953,
Serial No. 362,145

Claims priority, application Great Britain June 18, 1952

2 Claims. (Cl. 196—35)

This invention relates to the removal of vanadium and/or sodium from petroleum and petroleum products.

In the complete specification of the co-pending application No. 1029/51 there was described a process in which vanadium and/or sodium is/are removed from petroleum or petroleum products by contact with bauxite in the presence or absence of hydrogen and under conditions of temperature and pressure such that the vanadium and/or sodium is/are deposited on or incorporated with the bauxite. It was later discovered that the degree of vanadium and/or sodium removal under any given set of operating conditions tended to vary with bauxites of different origins.

It has now been found that vanadium and/or sodium in petroleum or petroleum products can be removed by treatment with fuller's earth.

According to the invention therefore, a process for removing vanadium and/or sodium from crude petroleum or a petroleum product comprises contacting the crude petroleum or petroleum product with fuller's earth, in the presence of hydrogen and under conditions of temperature and pressure such that vanadium and/or sodium is/are deposited on the fuller's earth.

The preferred ranges of operating conditions for the process are as follows:

Space velocity	v./v./hr.	0.5 to 2.0
Temperature	°F.	750 to 800
Pressure	p. s. i. ga.	500 to 1500
Hydrogen recycle rate	S. C. F./B.	1000 to 10,000

The process of the invention is particularly adaptable as a pre-treatment process for crude petroleum or petroleum products which are to be passed to a catalytic hydrogenation process for the removal of organically combined sulphur. For example, it has been found that in the hydrofining of crude petroleum and petroleum residues using a catalyst consisting of cobalt and molybdenum oxides supported on alumina, substantial proportions of vanadium and sodium are removed by and deposited on the catalyst and this deposition causes a steady decline in catalyst activity with hours on stream which

2

is not wholly recovered on regeneration in the conventional manner. The invention, therefore, also includes a continuous process wherein a petroleum feedstock containing vanadium and/or sodium is first treated with fuller's earth as above described, and is then passed to a hydrogenation zone for the removal of organically combined sulphur.

An example of the application of the invention to the treatment of a petroleum residue will now be given.

EXAMPLE

Sodium and vanadium removal from Kuwait 53% volume residue.

Conditions employed:

15	Feedstock	Kuwait 53% vol. residue
	Space velocity	v./v./hr.
	Temperature	°F.
20	Pressure	p. s. i. ga.
	Hydrogen recycle rate	1000
	S. C. F./B.	4000
	Direction of flow	Upward
	Duration of test	60 hours

25 Results obtained:

Pelleted fuller's earth

	Feedstock	Product (Bulk over 50 hrs.)
Vanadium, p. p. m.	41	27
Sodium, p. p. m.	39	33
Sulphur, percent wt.	3.89	3.24
Specific Gravity, 60° F./60° F.	0.958	0.940

35 We claim:

1. A process for removing vanadium and sodium from a crude petroleum feedstock comprising contacting the petroleum feedstock with a contact material consisting of fuller's earth at a space velocity in the range of about 0.5 to 2.0 v./v./hr. in the presence of hydrogen, and at a temperature within the range of about 750°-800° F., and at a pressure in the range of about 500-1500 p. s. i. ga. whereby the vanadium and sodium are deposited on the fuller's earth.

2. A process according to claim 1, comprising subsequently passing the treated feedstock to a hydrogenation zone for the removal of organically combined sulphur.
